[57] **CLAIM**

The ornamental design for a hook fastener for garments, substantially as shown and described.

DESCRIPTION

FIG. 1 is an exploded rear elevational view of a hook fastener for garments showing my new design;

FIG. 2 is an exploded front elevational view thereof;

FIG. 3 is a left side elevational view of the hook-receiving portion of the fastener in FIG. 1;

FIG. 4 is a left side elevational view of the hook portion of the fastener in FIG. 1;

FIG. 5 is a right side elevational view of the hook-receiving portion of the fastener in FIG. 1;

FIG. 6 is a right side elevational view of the hook portion of the fastener in FIG. 1; and

FIG. 7 is a top plan view of FIG. 1.
